JOSEPH PITTS AND JAMES K. PITTS, OF McLEAN, ILLINOIS.

Design No. 4,451, dated November 1, 1870.

DESIGN FOR A COAL-HOD.

The Schedule referred to in these Letters Patent and making part of the same.

To all whom it may concern :

Be it known that we, JOSEPH PITTS and JAMES K. PITTS, of McLean, in the county of McLean and in the State of Illinois, have invented a certain new and useful Design for a Coal-Hod; and do hereby declare that the following is a full, clear, and exact description thereof, reference being had to the accompanying drawing making a part of this specification, in which is shown a perspective side view of our improved coal-hod.

Our coal-hod is higher in front than in the rear, and has its upper front edge nearly square across, while its rear upper edge is rounded.

The edges of the sides are raised considerably above a line drawn from the center of the upper front edge to the center of the rear edge, the highest portion being in front of the lateral center of the hod. The sides of the hod are drawn in from the top to the bottom, and the base flares a little from top to bottom.

The advantage of the square front consists in the firm bearing it gives to the hod, when placed upon a stove, for discharging its contents; of the raised sides, in conforming closely to the gravity slope of the coals when the hod is filled, whereby there is less danger

of spilling the coals over any of its sides; of the upward front slope to the sides, in that, when the rear of the hod is raised in the act of pouring out coals, this slope conforms closely to the vertical sides of a stove; and there is less risk of the coals falling over the front sides of the hod upon the floor. In addition to these useful results of the peculiar shape of our hod, the whole design has artistic merits.

In making, however, this particular description of our coal-hod, and statement of the advantages of its construction, we do not wish to be understood as intending anything more than an enumeration of the merits of our design as a whole.

Having thus fully set forth the nature and merits of our invention,

What we claim as new is—

The design for a coal-hod, substantially as shown and described.

In testimony that we claim the foregoing, we have hereunto set our hands this 15th day of July, 1870.

JOSEPH PITTS.
JAMES K. PITTS.
